GOTTLIEB SPEISER, OF NUERMBERG, GERMANY, ASSIGNOR TO WESTINGHOUSE ELECTRIC & MANUFACTURING COMPANY, OF NEW YORK, N. Y., A CORPORATION.

AUTOMATIC SAFETY SWITCH FOR INDUCTION MOTORS.

Application filed August 1, 1925, Serial No. 47,611, and in Germany February 5, 1924.

My invention relates to improvements in automatic safety switches for induction motors.

An automatic safety switch for induction motors is already known on the tripping mechanism of which act three different relays viz: a starting relay, an overload relay and a low-voltage relay. The starting relay responds to a heavy current, such as occurs when the normal starting current is exceeded, the overload relay when the normal operating current is exceeded and the low-voltage relay when the network voltage drops or fails. While the starting relay and the low-voltage relay act directly upon the tripping mechanism of the switch, the overload relay controls a thermostat which trips the switch after a certain delay by means of the low-voltage relay.

The object of my invention is to reduce the number of relays required while maintaining substantially the same manner of operation of the switch.

According to my invention the switch controlling the thermostat to obtain delayed tripping is associated with the overload relay and the path of the relay armature is extended beyond the point of engagement with the thermostat controlling switch into the tripping mechanism of the safety switch for the purpose of being able to utilize the overload relay at the same time as a starting relay by causing immediate tripping upon heavy overloads.

In the drawing affixed to this specification and forming a part thereof, the improved safety switch is shown diagrammatically. The switch differs from the usual construction in the arrangement and the construction of the relay.

Like parts are indicated by like letters and numbers of reference in the various elements of the system.

Referring to the drawing it will be seen that in the lines of the automatic switches A_1 , A_2 , A_3 are connected the three release magnets F_1 , F_2 , F_3 . The tripping mechanism of the automatic switch A_2 is furthermore subjected to the action of a low-voltage relay G of known construction. The tripping magnet F_1 combines in itself the starting relay and the overload relay of the above described known construction. In the energizing coil 41 of the magnet F_1 the core 42 with the push-rod 43 is adapted to move ver-

tically. The core rests normally on the abutment 44. At its lower end it carries the insulated circuit closing member 45 of a thermostat controlling switch. Above the circuit closing member 45 are fixed at both sides of the core the contact springs 46, 46' in the insulating supports 47, 47'. The release magnet F_2 is constructed in a similar manner. The release or tripping magnet also shows the same general features, but the push-rod 43' is adapted to slide within the plunging core 42' and to be raised in relation to it. The push-rod rests normally upon the armature 12 of the low-voltage relay G while the core rests upon the abutment 44 as in the release magnet F_1 . The push-rod 43' has above the core a collar 48 by means of which it may be lifted by the core. The protective action of the improved switch is greater than in the known construction because the phase connected with the conductor 2 is also protected against too high a starting current.

Upon engagement of the circuit-closing members 45 with the contact springs 46, of the respective tripping mechanisms, a thermostatic switch e is energized to open the circuit of the holding coil on the low-voltage relay G to permit the actuation of its armature by its spring 13.

The switch operates in the following manner: as long as the current in the conductor 1 does not exceed the normal service current, the core 42 rests upon the abutment or stop 44. If the motor current exceeds the normal service current without exceeding the normal starting current the core 42 is raised and closes by means of the circuit closing member 45 the contact springs 46, 46' of the thermostat controlling switch. The contact springs are hereby put under tension. A further lifting of the core is opposed by the springs. The circuit to the winding of the thermostat E is then established and, as the thermostat becomes heated, it opens its switch 40 by actuating the pivoted armature 39 against the force of the restraining spring 38. The thermostat E then interrupts the circuit of the coil 7 of the low voltage relay G . The helical spring 13 now separates the armature 12 from its magnet pole and the armature throws the loose push-rod 43' against the roller 21 of the switch. However when the normal starting current is exceeded in the conductor 1, the tractive power of the magnet F_1 suffices to raise the core 42 in op-

position to the resistance of the springs 46, 46' so far that the push-rod 42 strikes the roller 21 and thereby effects the tripping of the switch.

5 When the current in the conductor 2 just exceeds the service current, the core 42' in the magnet F_2 is also raised and the thermostat switch is closed but the push-rod 43' remains upon the armature 12 of the low-voltage relay. If the current increases the core is raised higher, strikes the collar 48 and carries the push-rod 43' along with it. The dimensions and the arrangement are such that the push-rod 43 here also moves 10 the switch roller 21 upwards and trips the switch.

What I claim is:—

In an automatic switch of the class described, tripping mechanism, an electromagnet arranged to operate said tripping mechanism upon heavy overloads, contact members associated with said electromagnet, means including said electromagnet for operating said contact members at a lower current value than that required to operate the tripping mechanism, comprising a retarded relay connected to said contact members and a low-voltage magnet operated by said retarded relay and operative to control said tripping mechanism. 20 25 30

In testimony whereof I affix my signature.
GOTTLIEB SPEISER.
